LAWRENCE BRUEHL, OF BROOKLYN, NEW YORK, ASSIGNOR TO GAS REFRIGERATION CORPORATION, OF SCRANTON, PENNSYLVANIA, A CORPORATION OF DELAWARE

AUTOMATIC CONTROLLER FOR REFRIGERATING SYSTEMS

Application filed June 2, 1927. Serial No. 195,984.

This invention relates to the means employed for controlling the heating medium of a refrigerating apparatus of the intermittently operating absorption type.

Although it may be employed where the condenser and absorber are cooled by water and other regulating means are employed for controlling the flow of water, it is particularly intended for apparatuses of the air cooled type.

In carrying out my invention, I control the heating medium by the temperature of the evaporator or other part to be cooled and also by the temperature of the boiler, which latter preferably operates also as an absorber.

In the accompanying drawings, I have illustrated certain embodiments of my invention.

20 In Fig. 1 I have shown a construction in which two separate and independent controlling valves are employed in series in the conductor for the heating medium; and

25 In Figs. 2 and 3 I have shown two other forms in each of which only a single valve is used.

In the form shown in Fig. 1, there is a conductor for the heating medium. This is illustrated as a pipe 10 which may serve to 30 conduct combustible gas, steam, hot oil, or any other suitable fluid heating medium, but an electric conductor would be used if electricity were the heating medium. In this conductor there is a pair of valves 11 and 12 35 for controlling the flow of the heating medium. Within the broad meaning of the term "valve" I include a switch or other means suitable for controlling an electric heating current.

40 Within the evaporator 13 or associated in heat interchanging relationship thereto, there is employed a cell or tube 14 for a fluid medium which will expand and contract with the changes in temperature in the evaporator and this is connected to the valve 11 by suitable operating mechanism.

In the boiler-absorber 15 there is employed a similar cell or tube 16 for operating the valve 12.

50 The mechanism for operating the two

valves may be similar and that illustrated is constructed and operated as follows:

The valve stem 17 intermediate of its ends engages a lever 18 which is pivoted in one end of the valve casing 19. Also within the casing there is a bellows 20 which forms a partition subdividing the chamber into two compartments. The end wall 21 of the diaphragm is pivoted by means of a lug 22. At one side of the center and projecting inwardly from the center is a pin 24. The pin 24 and the lever 18 are independently movable and are capable of being brought into axial alignment. Between the two is a coil spring 25 which tends to press them in opposite directions and serves to snap the valve to open or closed position. Each valve casing has connections whereby it may be secured in series in the conductor for heating medium and each valve has an adjustable stop 26 whereby the opening movement of the valve may be limited. The heating medium may fill the portion of the casing around the spring 25 and above the bellows, while the cell 14 is connected by a conduit 27 to the compartment 70 of the valve casing below or outside of the bellows. The expansion and contraction of the fluid medium in the cell causes varying pressure on the bellows and will operate to collapse or contact the bellows under high 75 pressure and permit the bellows to expand at low pressure.

The end wall of the bellows being pivoted at one side, the upper end of the pin 24 will move back and forth to opposite sides of the 85 lower end of the lever 18.

The operation of the construction illustrated is substantially as follows:

The parts are shown in such position that the two valves are open. This is the position the parts are to occupy at the beginning of the heating period. There is comparatively low temperature in the boiler-absorber as the gas is passing off freely to the condenser and there is a comparatively high temperature in the evaporator as there is no evaporation or cooling effect taking place. As the heating of the boiler-absorber continues the operation will reach a point at which substantially all of the ammonia or other refrigerant

erant gas has been driven off, and the temperature will rise to such a point in the boiler-absorber that the fluid in the cell 16 in expanding will exert sufficient pressure on the bellows of the valve 12 to collapse the latter 5 and swing the pin 24 from the position indicated, toward the right to such a point that it will pass the axis of the lever 18. The spring 25 will then instantly move the lever 18 to the opposite limiting position and close 10 the valve 12. The supply of heating medium of the boiler-absorber will thus stop even though the valve 11 is open. The temperature of the boiler-absorber will then begin to drop and evaporation in the evaporator will 15 begin.

As the evaporator temperature drops the pressure thermostatic medium in the cell 14 will decrease and the bellows 20 of the valve 11 will expand to swing the pin 24 toward 20 the right and close the valve 11.

The cooling of the boiler-absorber will also cause the contraction of the thermostatic medium in the cell 16 and the pin 24 of the 25 valve 12 will swing to the left and open the valve 12. The parts are so adjusted that the valve 11 will close before the valve 12 opens and therefore the opening of the valve 12 does not turn on the heating medium. The 30 operation will continue with the valve 11 closed and the valve 12 open, until the refrigerating medium in the evaporator is all evaporated or the absorbent in the boiler-absorber cannot absorb any more of the refrigerant. The temperature of the evaporator will then increase to such a point that the 35 pin 24 will again swing toward the left and snap the valve 11 to open position. As the valve 12 is already open the heating medium will be turned on.

Obviously the temperature range of the boiler-absorber will be very much greater than that of the evaporator and therefore the size of the cells for the thermostatic medium, 40 the strength of the diaphragm, the relative proportion of the parts, etc. may be varied to effect the opening and closing of the valves at the desired temperatures. For instance, the parts may be designed so that the valve 45 11 will open when the evaporator temperature reaches 31° F. and will close at 27° F., while the valve 12 will open when the boiler-absorber gets down to 130° F. and will close at 260° F. Obviously the boiler-absorber may reach 50 a temperature very much below 130° F., and the evaporator may reach a temperature considerably above 31° F.

The heating starts when the evaporator temperature reaches its high limit of 31° F. 55 and the heating stops when the boiler-absorber reaches its high limit of 260° F.

Of course, the apparatus may be adjusted so that the controlling temperatures are higher or lower than those above mentioned. 60 This adjustment may be secured by the ad-

justing screws 26. These limit the extent to which the valves may be opened and therefore control the extent to which the pins 24 are moved toward the right before the valves snap shut.

From a manufacturing standpoint, preferably the mechanism for operating the two valves 11 and 12 is identical, although in assembling, the pivotal support 22 for one valve is placed at one side of the casing and for the other valve it is placed at the opposite side of the casing. The temperature range is preferably controlled by the character and quantity of the thermostatic fluid employed in the cells 14 and 16.

It will be noted that the apparatus is fool-proof and self-starting, in that it automatically takes care of any abnormal operating condition and automatically returns to normal working condition. If the heating medium be shut off at some other point in the line the temperature in the evaporator will rise above 31° F. to open the valve 11 and the temperature in the boiler-absorber will drop below 130° F. to open the valve 12. Therefore, when the heating medium is again turned on, both valves will be open to start a new cycle of operations. If the heating medium be combustible gas, there will, of course, be provided an automatic safety pilot 95 light which will insure the lighting of the gas when it is turned on.

As the valve casing and operating mechanisms for the valves 11 and 12 are entirely independent, it will be evident that they may 100 be placed at separate points in the conductor 10, and either directly adjacent to each other or spaced to any distance apart.

In the construction shown in Fig. 2 a single valve 30 is employed for the heating medium. Two separate thermostatic power elements are employed which may be similar to those shown in Fig. 1, but they are both operatively connected to this single valve. Instead of using fluid thermostatic power elements, I have illustrated expansible rods. A tube 31 is connected to the valve casing 32 and within it is a rod 33. The rod and tube are connected together at the outer end and they are of such material as to have different coefficients of expansion. On the opposite side of the casing 32 there is a similar tube 34 with its expansible rod 35. Preferably the tube 31 extends into the boiler while the tube 34 extends into the evaporator.

The inner ends of the rods are threaded or provided with rack teeth, and they are spaced apart and in engagement with opposite sides of a roller or pinion 36. The endwise movement of either rod will cause the rotation of 125 the pinion. The pinion has a lever arm 37 which engages one end of the spring 38. The opposite end of the spring is connected to a lever 39 which is pivoted intermediate of its ends and serves to operate the valve 30.

The operation of this apparatus is as follows:

At the end of the absorption period the boiler-absorber is cooled and the end of the rod 33 is at the extreme position toward the right, that is in engagement with the adjusting screw 40. This is because the tube 31 has a greater coefficient of expansion than the rod 33. The temperature of the evaporator has begun to rise and the rod 35 moves toward the left. This causes the lever 37 to swing toward the right to a point beyond the axial projection of the lever 39. Thereupon the spring causes the valve 30 to snap to open position. As the boiler warms up the rod 33 moves toward the left and swings the lever 37 in the opposite direction. When the temperature of the boiler reaches the predetermined point the lever 37 will then swing over to such a point that it comes to the opposite side of the axial projection of the lever 39 and the valve 30 snaps to closed position. The time of this movement is modified due to the fact that the absorber is also warming up at the same time. The screw 41 opposite the end of the rod 35 serves to regulate the temperature of the boiling period and to keep this temperature fixed at a certain point. During the latter part of the boiling period the rod 35 rests against the screw 41. The rod 33 is still free to move toward the left so that the lever 37 turns counterclockwise until the valve plunger is shifted and the heating medium is shut off. Now both rods start to move to the right and their speeds are proportional to the decrease in temperature of the evaporator and the boiler-absorber. The rod 33 moves first because the boiler temperature decreases rapidly. Hence the lever 37 turns clockwise, but after a limited period and before the valve is again shifted, the rod 35 starts to move from this rest position against the screw 41 and in so doing slows down the clockwise movement of the lever 37. Eventually it stops this movement and reverses it when the rod 33 reaches the regulating screw 40. As the rod 33 cannot move any further, but the rod 35 can, the lever 37 will be eventually moved to such position that the lever is again shifted and the next boiling period begins.

The operation of this mechanism is also completely fool-proof. If the evaporator is under an overload the temperature in the evaporator will not go down far enough to move the rod 35 from its rest position on the screw 41. In this case the rod 33 swings the lever 37 to start the next boiling period and the length of the cycle is a function of the rate of boiler radiation. Under such overload conditions the control of the machine is solely by the power element of the boiler. The machine may be shut down at any point in the cycle and the mechanism will automatically bring the valve 30 to open position

to start a new heating period when the apparatus is permitted to start operating again.

The movement of the rods 33 and 35 are parallel and in the same direction with increasing temperature.

Another construction operating on this principle is shown in Fig. 3. Here there are employed two bellows 42 and 42^a mounted in casings 43 and 44 and connected to rods 45 and 46. The two casings may be secured to a supporting wall 47 and the two rods may be connected by a link 48. The connection should be such as permits a sliding at one end or the other. As shown the link 48 is connected to the rod by a pivot pin 49 and to the rod 46 by a slot 50 and pin 51. The rod 46 has a collar 52 for limiting its inward movement through a guide 53 and the rod 45 is movable in a sleeve 54 which is adjustable lengthwise in a guide 56 so as to limit the outward movement of the rod. Thermostatic power elements are connected by tubes 57 and 58 to the bellows casings 43 and 44. In these bellows there are springs 59 tending to expand them against action of the thermostatic power fluids. The tube 57 is connected to the thermostatic element in the boiler, while the tube 58 is connected to the thermostatic element of the evaporator. The link 48 is connected in any suitable manner to such a valve as that shown in Fig. 2. The link is illustrated as having a bail 60 secured thereto intermediate of its ends and having a portion projecting into engagement with a spring 38. This spring serves to operate a valve lever 39 and valve 30 which may be substantially the same as shown in Fig. 2.

The operation is as follows:

The parts are shown in the position which they occupy during the latter part of the absorption period. The bellows 42 is in a fixed position because the stop 52 is in engagement with the guide 53. The evaporator contains no liquid refrigerant and is not generating any more cold so that the temperature increases and the bellows 42^a contracts. At a certain point corresponding with the desired temperature, the bellows will reach such a position that the valve is shifted and the boiling starts. Now both of the rods 45 and 46 move outwardly, but after a short time the travel of the rod 45 is stopped because the bellows rests against the lower end of the bushing or stop 54. The rod 46 will continue to move outwardly to swing the link 48 and the bail 60 until at the end of the boiling period the valve 30 is shifted to closed position. The absorption period now starts and the rod 46 moves back into the casing 43 as the temperature in the boiler decreases. A short time later when the cold is generated in the evaporator the rod 45 also moves back. By the back movement, the valve lever is not shifted and the valve remains closed. Should the rod 45 fail to go back due overload in

the evaporator, the rod 46 would serve to swing the link 48 and open the valve for the start of a new boiling period. The temperature may be regulated by the adjustment of 5 the nut 52 and the bushing 54. The valve may be placed in any desired position in respect to the link 48 so that the tilting of the link moves the end of the spring 38 over the desired range. The bail 60 may extend 10 downwardly from the link, or as shown in dotted lines a projection may extend upwardly from the link and directly to the spring of a valve disposed above.

Having thus described my invention, what 15 I claim as new and desire to secure by Letters Patent is:

1. A refrigerating apparatus of the intermittently operating absorption type, including a conductor for the heating medium for 20 the boiler-absorber, a pair of separate identic interchangeable valves in said conductor for controlling the supply of the heating medium, each of said valves being provided with a movable fluid pressure operated member, re- 25 silient connections between said member and the valve for holding the latter in either closed or full open position, and adjustable means for limiting the opening movement, means for moving the member of one of said 30 valves in accordance with the temperature in the evaporator, and means for moving the other of said members in accordance with the temperature in the boiler-absorber.

2. A refrigerating apparatus of the intermittently operating absorption type, including a conductor for the heating medium for 35 the boiler-absorber, a pair of separate identic interchangeable valves in said conductor for controlling the supply of the heating medium, each of said valves being provided with a 40 movable fluid pressure operated member and resilient connections between said member and the valve for holding the latter in either closed or full open position, means for moving the member of one of said valves in accordance with the temperature in the evap- 45 orator, and means for moving the other of said members in accordance with the temperature in the boiler-absorber.

3. A refrigerating apparatus of the intermittently operating absorption type having a conduit for supplying heating medium to the boiler-absorber, a pair of separate and independent reciprocating valves in series in said conduit, a pair of expansible bellows, snap connections between each bellows and its corresponding valve for moving the valve to either of its two opposite limiting positions, 55 an expansible fluid container in thermal connection with the evaporator and connected to one bellows, and a similar expansible fluid container in the boiler-absorber and connected to the other bellows whereby the heating 60 medium is controlled solely by the tempera- 65

ture in the boiler-absorber and the evaporator.

4. A refrigerating apparatus of the intermittently operating absorption type, including a conduit for supplying heating medium, valve mechanism for controlling said conduit, a pair of containers for expansible fluid, one disposed in thermal connection with the evaporator and the other in thermal connection with the boiler-absorber, a pair of valve operating members, one moving in accordance with the pressure in one of said containers and the other movable in accordance with the pressure in the other container, and reversible snap connections between said valve mechanism and said members.

Signed at New York in the county of New York and State of New York this 21st day of May A. D. 1927.
